UNITED STATES PATENT OFFICE.

HENRY GIBSON O'NEILL, OF NEW YORK, N. Y., ASSIGNOR OF ONE-HALF TO CONRAD HUBERT, OF NEW YORK, N. Y.

ENGINE-STARTER.

1,105,297.

Specification of Letters Patent. Patented July 28, 1914.

Application filed May 29, 1913. Serial No. 770,619.

To all whom it may concern:

Be it known that I, HENRY GIBSON O'NEILL, a citizen of the United States, residing in the borough of Manhattan, city of New York, in the county of New York and State of New York, have invented certain new and useful Improvements in Engine-Starters, of which the following is a specification, reference being had therein to the accompanying drawings, forming part thereof.

My invention relates to electrically operated engine starters for starting internal combustion engines, particularly those of automobiles, and the present improvements relate more particularly to means for connecting a combined dynamo and motor, or dynamo-motor, (also called a "dynamotor") with the engine to start the engine at one speed ratio between the dynamo-motor operated as a motor and the engine, and for connecting the engine with the dynamo-motor to actuate the dynamo-motor as a dynamo at a different speed ratio between the engine and dynamo-motor.

An important object of my invention is to produce an electrically operated engine starter particularly well adapted for application to automobiles which have already been built and in which no provision has been made for the accommodation of an engine starter; and, more particularly, to produce such an engine starter adapted to be installed at the front of the car.

Other objects of my invention are inexpensiveness of manufacture and installation, convenience of installation, simplicity and compactness of construction, durability, reliability in operation, keeping the apparatus cool, accessibility, automatic change of the dynamo-motor from a motor to a dynamo and vice versa, neatness and symmetry of appearance, and other advantages which will hereinafter appear.

My invention includes an improved arrangement and combination of engine-starting electric motor, gearing and intermediary connections with the engine, the motor being at one side of the engine shaft and the gearing at the other, with the engine-connected parts between the motor and the gearing.

My invention also includes, in combination, reducing gearing, having novel clutching means incorporated therein, and my in-

vention further includes features of construction and combinations of parts as will appear from the following description.

I shall now describe the electric starter embodying my invention illustrated in the accompanying drawings and shall thereafter point out my invention in claims.

Figure 1 is a front elevation on a reduced scale of an automobile equipped with my improved engine starter. Fig. 2 is a vertical longitudinal section of the starter casing with the mechanism mostly in elevation, but partly in section. Fig. 3 is a transverse section on a plane indicated by the line 3—3 of Figs. 2 and 7. Fig. 4 is a similar view indicated by the line 4—4. Fig. 5 is a partial horizontal longitudinal section on a plane indicated by the line 5—5 of Fig. 2. Fig. 6 is a partial transverse section on a plane indicated by the line 6—6 of Fig. 2 as viewed from the right. Fig. 7 is an enlarged vertical longitudinal section of the mechanism appearing at the center and left in Fig. 2.

The parts of the engine-starting mechanism are distributed substantially equally as to weight at both sides of the engine shaft 1 and are contained within an outer casing of symmetrical appearance, as appears in Figs. 1 and 2. The symmetrical casing is made up of similar end caps 2, similar cylindrical shells 3 and a symmetrical gear cover 4 at the middle; all rigidly joined together, as by longitudinal rods 5, to form a symmetrical strong and rigid combined casing and supporting frame, of which the end caps 2 are adapted to be bolted to the side frame of an automobile chassis at the front of the engine, as appears in Figs. 1 and 2.

Any suitable construction of dynamo-motor 6 may be employed. The armature shaft 7 of the dynamo-motor 6 extends the length of the supporting and inclosing casing and at its ends is shown as mounted in ball bearings, comprising supporting bearings and thrust bearings, in the end caps 2. The armature shaft 7, at the other side of the engine shaft 1 from the dynamo-motor 6, is directly connected to a two-part gearing carrier 8, which also forms a gear-inclosing case, through a cone friction clutch 9 controlled by a centrifugal governor having governor balls 10.

Two concentric spur pinions 11 and 12, shown as of the same diameter, but differing as to number of teeth, are located cen-

trally of the gearing carrier 8 and concentric with the armature shaft 7. The pinion 11 is shown as having thirteen teeth and the pinion 12 as having fourteen teeth, the spacing of the teeth in these two pinions being correspondingly slightly different. The thirteen-toothed pinion 11 is an abutment pinion which remains stationary during the engine-starting operation, and the fourteen-toothed pinion 12 is an engine-starting pinion which is rotated to effect the starting of the engine.

The abutment pinion 11 is shown as keyed to an inner anchor sleeve 13, which immediately surrounds the armature shaft 7 and extends back to the dynamo-motor 6, where it is adapted to be anchored against rotation in the direction of torque corresponding to the engine-starting operation by means 15 of a unidirectional clutch or ratchet device shown as comprising a ratchet disk 14 keyed on the end of the anchor sleeve 13, and a stationary cup-shaped clutch ring 15 fixed on a journal box 16 supported by the central 20 gear cover 4, usual clutch balls being interposed, as shown, between the ratchet disk 14 and the gripping cup 15.

The engine-starting pinion 12 is fixed on the inner end of an engine-connected and 25 engine-starting outer sleeve member 17 which surrounds the inner or anchor sleeve 13. Rotation at a reduced rate, corresponding to the difference in the number of teeth between the abutment pinion 11 and the engine-starting pinion 12, is imparted to the 30 engine-starting sleeve 17, through the engine-starting pinion 12, by means of one or more, shown as two, planetary pinions carried by the gearing carrier 8 and journaled on bushings 18 supported by bolts 19 which also hold together the two parts of the gearing carrier 8. Each of the planetary pinions 20 and 21 meshes with both the abutment pinion 11 and the engine-starting pinion 12. It should be noted that one planetary pinion would impart the desired rotation to the engine-starting pinion 12, but two are used for increased strength and also for convenient centrifugal balancing of the 45 parts carried by the gearing carrier 8, and more than two planetary pinions could be employed if desired. The planetary pinion 20 is shown as having one set of teeth which mesh with aligned teeth in the concentric 50 abutment and engine-starting pinions 11 and 12. The planetary pinion 21 has two sets of teeth in offset relation so as to properly mesh with the offset teeth of the pinions 11 and 12 at a point diametral to the meshing point of the pinion 20. This relationship is readily apparent by comparing Figs. 3 and 4.

As the planetary pinions revolve about the concentric pinions 11 and 12, it will be seen 55 that for each such revolution, corresponding

to a rotation of the armature shaft 7, the engine-starting pinion 12 will be stepped up or moved forward an angular distance equal to the difference in the number of teeth it has over the abutment pinion 11, 70 which in the construction illustrated is one tooth. From this it appears that it will require fourteen rotations of the armature shaft 7 to impart one rotation to the engine sleeve 17.

It should be explained that, in accordance with the same principle, to obtain a different ratio of reduction, the total number of teeth in the concentric equally diametered pinions, such as 11 and 12, should be increased or decreased by the same number. For example, if the abutment pinion be given twenty teeth, the engine-starting pinion should have twenty-one teeth; giving in such case a gear reduction of one to twenty-one. Of course, the common diameter of the pinions 11 and 12 may be varied to accommodate the desired number of teeth of proper size and strength. It should be noted that the 80 number of teeth on the planetary pinions 90 does not affect the ratio of reduction, and these pinions may be of any diameter and with any corresponding number of teeth which will smoothly mesh with the central pinions 11 and 12, but should be as 95 small as permissible, so as to economize space. In the construction illustrated, each of the planetary pinions has thirteen teeth. The teeth of all the intermeshing pinions 11, 12, 20 and 21 are shown as straight spur 100 teeth, but, of course, other forms of gear teeth, for example, herringbone teeth or spiral teeth, could be employed if desired without in any manner affecting the principle of operation.

It will be observed that the stepping forward of the rotative engine starting pinion 12 relatively to the stationary abutment pinion 11 is due to a wedging or cam action of the teeth of the planetary pinions 20 and 21 exerted between the teeth of the anchored abutment pinion 11 and those of the movable pinion 12. This reduction gearing permits a strong and compact construction of few parts.

It should be noted that while, in accordance with the principle of this gearing, it is not necessary to have pinions or gears of differing diameters, as is usual, this fact being abundantly apparent from the drawings in connection with the preceding explanation, yet this same principle by reason of which a gear is stepped forward, or back, if desired, could as well be applied to gearing in which the gear members vary as to relative diameters after the manner of ordinary gearing. For example, the engine-starting pinion 12 could be of larger diameter than the abutment pinion 11 and have any convenient number of teeth, the ends of the planetary pin-

meshing with the spiral teeth of the spiral-toothed pinion having the clutch member to receive rotation therefrom or to impart rotation thereto and adapted to shift the 5 slideable clutch member of the spiral-toothed pinion into engagement with the clutch member on the gearing carrier to operate the dynamo-motor as a dynamo from the slideable clutch member through the gearing 10 carrier.

11. An engine starter comprising, in combination with the engine shaft, a dynamo-motor having an armature shaft, a planetary gearing carrier concentrically connected 15 to the armature shaft of the dynamo-motor to receive rotation therefrom or to transmit rotation thereto, an abutment member concentric with the armature shaft and gearing carrier, a ratchet device controlling the 20 abutment member so that it can rotate in one direction only, an anchor sleeve concentric with the armature shaft and carrying the abutment member, an engine-connected engine-starting sleeve concentric with 25 the armature shaft, an engine-starting member fixed on the engine-connected sleeve, planetary gearing journaled on the gearing carrier and co-operative with the abutment member and the engine-starting member to 30 impart rotation from the dynamo-motor operated as a motor to the engine-connected sleeve, a spiral-toothed pinion rotatable with and slideable longitudinally of the engine-connected sleeve, the spiral-toothed pinion 35 and the gearing carrier having co-operative clutch members adapted to be engaged or disengaged by the longitudinal movement of the spiral-toothed pinion to lock the latter to the gearing carrier or to disconnect 40 it therefrom, and a spiral-toothed gear on the engine shaft meshing with the spiral-toothed pinion and adapted to shift such pinion longitudinally to engage the clutch members for operating the dynamo-motor 45 as a dynamo through the gearing carrier without relative movement of the parts of the gearing.

12. In an engine starter, the combination of an engine-connected gear, an engine-starting member, a pinion permanently rotative with the engine-starting member and permanently meshing with such gear and adapted to be shifted longitudinally in one direction or the other according as the 55 gear or the pinion is the driver, such pinion having a clutch member, and a second clutch member with which the clutch member of the pinion is adapted to be engaged or disengaged by reason of the 60 longitudinal shifting of the pinion on the one direction or in the other.

13. In an engine starter, the combination of an inclined-tooth gear permanently rotatively connected with the engine, an engine-starting member, an inclined-tooth pinion

rotatively carried by the engine-starting member and permanently meshing with such gear and adapted by reason of the inclination of the teeth of the gear and the pinion to be shifted longitudinally in one direction or the other according as the gear drives the pinion from the engine or the pinion drives the gear from the engine-starting member, the pinion having a clutch member, and a second clutch member with which the clutch member of the pinion is adapted to be engaged or disengaged by reason of the longitudinal shifting of the pinion in the one direction or the other.

14. In an engine starter, the combination of a spiral-toothed gear rotatively connected with the engine, a rotative engine-starting member having its axis transverse to that of the spiral-toothed gear, a longitudinally shiftable spiral-toothed pinion permanently rotative with the engine-starting member and permanently meshing with the spiral-toothed gear so as to be shifted longitudinally by end thrust on the pinion in the one direction or the other according as the pinion drives the gear from the engine-starting member in an engine-starting operation or the gear drives the pinion from the engine after the engine has started, such pinion having a clutch member, and a second clutch member with which the clutch member of the pinion is adapted to be engaged or disengaged by the longitudinal shifting of the pinion in the one direction or the other.

15. An engine starter comprising, in combination, a dynamo-motor, a set of gearing operative as speed-reducing gearing from the dynamo-motor to the engine and as speed-multiplying gearing from the engine to the dynamo-motor, a second set of gearing constituting speed-reducing gearing connecting the dynamo-motor to the first set of gearing and providing for the operation of the dynamo-motor as a motor to effect an engine-starting operation through both sets of gearing operating as speed-reducing gearing, and automatically acting clutching means for discontinuing the operation of the second set of gearing and connecting the first set of gearing directly with the dynamo-motor to operate the dynamo-motor as a dynamo without the operation of the second set of gearing and with the first set of gearing operating as speed-multiplying gearing.

16. An engine starter comprising, in combination, an engine-connected member, an engine-starting electric motor at one side of the engine-connected member, speed-reducing gearing for the motor at the other side of the engine-connected member, and power-transmitting connections connecting the speed-reducing gearing and the engine-connected member including clutching means for connecting the motor to such member to effect an engine-starting operation.

- gine-starting operation from the motor through the reducing gearing.
4. An engine starter comprising, in combination, an engine shaft, an engine-starting electric motor at one side of the engine shaft, speed-reducing gearing for the motor at the other side of the engine shaft, a connecting shaft between the motor and the gearing extending transverse to the engine shaft, and 10 an engine-connected sleeve surrounding said connecting shaft and connected with the gearing for effecting an engine-starting operation from the motor through the reducing gearing.
5. An engine starter comprising, in combination, an engine shaft, a dynamo-motor at one side of the engine shaft having an armature shaft extending transverse to the engine shaft to the other side of the engine 20 shaft, speed-reducing gearing connected to the armature shaft at the other side of the engine shaft from the dynamo-motor, an engine-connected sleeve surrounding the armature shaft intermediate the dynamo-motor and gearing, a spiral-toothed gear fixed on the engine shaft, a spiral-toothed pinion rotatable with and slidable longitudinally of the engine-connected sleeve, and clutching means controlling the gearing and actuated 30 by sliding movement of the spiral-toothed pinion imparted by the spiral-toothed gear on the engine shaft.
6. An engine starter comprising, in combination, a dynamo-motor, an engine-connected engine-starting member, speed-reducing gearing connecting the dynamo-motor to the engine-starting member, means co-operative with the speed-reducing gearing and engine-starting member for starting the engine from the dynamo-motor operated 35 as a motor, and a clutch device adapted to be shifted by the engine to form a connection for actuating the dynamo-motor as a dynamo without relative movement of the parts of the gearing.
7. An engine starter comprising, in combination, a dynamo-motor, a planetary gearing carrier adapted to be rotated by the dynamo-motor, an engine-connected engine-starting member concentric with the gearing carrier, planetary reducing gearing connecting the gearing carrier and the engine-starting member, means co-operative with the planetary reducing gearing and engine-starting member for starting the engine from the dynamo-motor operated as a motor, and a clutch device, one member of which is carried by the gearing carrier and the other member of which is concentric with 50 the engine-starting member and movable longitudinally thereof by the engine to connect the engine-starting member to the gearing carrier so as to operate the dynamo-motor as a dynamo without relative movement of the parts of the gearing.
8. An engine starter comprising, in combination with the engine shaft, a dynamo-motor, an engine-connected engine-starting member, speed-reducing gearing connecting the dynamo-motor to the engine-starting member, a spiral-toothed gear fixed on the engine shaft, a spiral-toothed pinion forming a permanent connection between the engine-starting member and such spiral-toothed gear and having a clutch member, 70 means co-operative with the reducing gearing and other connections for starting the engine from the dynamo-motor operated as a motor, and means including a second clutch member with which the clutch member of the spiral-toothed pinion is adapted to be engaged by the engine to operate the dynamo-motor as a dynamo without relative movement of the parts of the gearing.
9. An engine starter comprising, in combination with the engine shaft, a dynamo-motor, an engine-connected engine-starting member, speed-reducing gearing connecting the dynamo-motor to the engine-starting member, a spiral-toothed gear fixed on the engine shaft, a spiral-toothed pinion forming a permanent connection between the engine-starting member and such spiral-toothed gear and having a clutch member, 80 means co-operative with the reducing gearing and other connections for starting the engine from the dynamo-motor operated as a motor, and means including a second clutch member with which the clutch member of the spiral-toothed pinion is adapted to be engaged by the engine to operate the dynamo-motor as a dynamo without relative movement of the parts of the gearing.
10. An engine starter comprising, in combination with the engine shaft, a dynamo-motor, a planetary gearing carrier connected to the armature shaft of the dynamo-motor to receive rotation therefrom or to transmit rotation thereto, an abutment member concentric with the gearing carrier and mounted for movement in one direction only of rotation, an engine-connected engine-starting member concentric with the abutment member, planetary reducing gearing connecting together the gearing carrier and the abutment member and the engine-starting member, to impart rotation to the engine-starting member at a reduced rate for starting the engine at a reduced speed ratio from the dynamo-motor operated as a motor, a combined spiral-toothed pinion and clutch member rotatable with and slidable longitudinally of the engine-starting member, the gearing carrier having a clutch member co-operative with the slidable clutch member, and a spiral-toothed gear whose axis is disposed transverse to that of the armature shaft fixed on the engine shaft and 100
11. An engine starter comprising, in combination with the engine shaft, a dynamo-motor, a planetary gearing carrier connected to the armature shaft of the dynamo-motor to receive rotation therefrom or to transmit rotation thereto, an abutment member concentric with the gearing carrier and mounted for movement in one direction only of rotation, an engine-connected engine-starting member concentric with the abutment member, planetary reducing gearing connecting together the gearing carrier and the abutment member and the engine-starting member, to impart rotation to the engine-starting member at a reduced rate for starting the engine at a reduced speed ratio from the dynamo-motor operated as a motor, a combined spiral-toothed pinion and clutch member rotatable with and slidable longitudinally of the engine-starting member, the gearing carrier having a clutch member co-operative with the slidable clutch member, and a spiral-toothed gear whose axis is disposed transverse to that of the armature shaft fixed on the engine shaft and 110
12. An engine starter comprising, in combination with the engine shaft, a dynamo-motor, a planetary gearing carrier connected to the armature shaft of the dynamo-motor to receive rotation therefrom or to transmit rotation thereto, an abutment member concentric with the gearing carrier and mounted for movement in one direction only of rotation, an engine-connected engine-starting member concentric with the abutment member, planetary reducing gearing connecting together the gearing carrier and the abutment member and the engine-starting member, to impart rotation to the engine-starting member at a reduced rate for starting the engine at a reduced speed ratio from the dynamo-motor operated as a motor, a combined spiral-toothed pinion and clutch member rotatable with and slidable longitudinally of the engine-starting member, the gearing carrier having a clutch member co-operative with the slidable clutch member, and a spiral-toothed gear whose axis is disposed transverse to that of the armature shaft fixed on the engine shaft and 120
13. An engine starter comprising, in combination with the engine shaft, a dynamo-motor, a planetary gearing carrier connected to the armature shaft of the dynamo-motor to receive rotation therefrom or to transmit rotation thereto, an abutment member concentric with the gearing carrier and mounted for movement in one direction only of rotation, an engine-connected engine-starting member concentric with the abutment member, planetary reducing gearing connecting together the gearing carrier and the abutment member and the engine-starting member, to impart rotation to the engine-starting member at a reduced rate for starting the engine at a reduced speed ratio from the dynamo-motor operated as a motor, a combined spiral-toothed pinion and clutch member rotatable with and slidable longitudinally of the engine-starting member, the gearing carrier having a clutch member co-operative with the slidable clutch member, and a spiral-toothed gear whose axis is disposed transverse to that of the armature shaft fixed on the engine shaft and 130

operated as a dynamo, without storage of the energy. In case of high engine speed, the centrifugally controlled clutch 9 will slip, so that the dynamo-motor 6 will be 5 driven as a dynamo at a substantially uniform maximum speed, as is well known to be desirable.

Upon stopping the engine, the clutch members 23^a and 8^a will automatically become 10 disengaged by reason of the "dying kick" or final reverse movement of the engine shifting the spiral-toothed pinion longitudinally to withdraw the clutch member 23^a from the clutch member 8^a. A coiled 15 thrust spring 26 interposed between the clutch members 8^a and 23^a assists this final back kick of the engine, or will itself separate and disengage the clutch members should the final engine kick fail to occur. 20 The disengagement of the clutch members 8^a and 23^a upon the stoppage of the engine leaves the mechanism in condition for effecting the starting of the engine.

It should be noted that the spiral-toothed 25 pinion 23 is always in mesh with the engine-connected spiral-toothed gear 22 ready to transmit energy either to or from the engine shaft 1 effectively and noiselessly, and also to effect automatically, positively and noiselessly 30 the engagement or disengagement of the co-operative clutch members 23^a and 8^a for automatically controlling the speed ratio of the transmission of energy to and from the dynamo-motor and the engine. It 35 should be further noted that the spiral gear 22, the spiral pinion 23 and the engine-starting sleeve 17 are all permanently rotatively connected with the engine shaft 1 and rotate therewith during both energy-generating 40 and engine-starting operations, and may be correctly referred to as engine-connected parts or engine-connected members. The spiral gear 22 and the spiral pinion 23 transmit power during the energy-generating and 45 also during the engine-starting operation, but the engine-starting sleeve 17 transmits power only during an engine-starting operation and rotates idly during the energy-generating operation.

50 The arrangement of the dynamo-motor 6 at one side of the engine shaft 1 at the front of the automobile, and the reducing gearing, carried by the gearing carrier 8, at the other side of the engine shaft, with the 55 engine-connected parts, including the spiral-toothed clutch pinion 23, between the dynamo-motor and the gearing, utilizes to the best advantage the available space on the automobile and also provides for carrying 60 out the hereinbefore described mechanical features of the invention by means of which automatic control and effectiveness of operation are secured.

It should be understood that the combined 65 engine shaft and starter shaft 1 may extend

back as an integral piece through the engine, or this shaft may be made up of a plurality of joined alined parts, as desired or according to the requirements of the installation.

70 By reason of its exposed condition at the front of the automobile, the draft of air from the traveling movement will keep the starting apparatus cool. This cooling effect is of particular value in reference to the 75 dynamo-motor 6 operated as a dynamo, which occurs during long periods in generating electrical energy for the several purposes hereinbefore mentioned and during which time the heat is carried away by the 80 currents of cooling air to which the dynamo-motor is fully exposed, the effectiveness of such cooling arrangement becoming evident by the continued running of the dynamo-motor 6 as a dynamo without objectionable 85 heating.

It is obvious that various modifications may be made in the construction shown in the drawings and above particularly described within the principle and scope of 90 my invention.

I claim:

1. An engine starter comprising, in combination, an engine shaft, an engine-starting electric motor at one side of the engine shaft, speed-reducing gearing for the motor at the other side of the engine shaft, and an engine-connected part connected with the engine shaft between the motor and the 95 gearing and connected with the gearing for 100 effecting an engine-starting operation from the motor through the reducing gearing.

2. An engine starter comprising, in combination, an engine shaft, a dynamo-motor at one side of the engine shaft, speed-reducing gearing at the other side of the engine shaft, an engine-connected part connected with the engine shaft between the dynamo-motor and the gearing and connected with the 105 gearing for effecting an engine-starting 110 operation through the gearing from the dynamo-motor operated as a motor, and automatically acting clutching means for discontinuing the operation of the gearing and connecting the engine-connected part 115 with the dynamo-motor to operate the dynamo-motor as a dynamo without the operation of the gearing.

3. An engine starter comprising, in combination, an engine shaft, an engine-starting 120 electric motor at one side of the engine shaft and having its armature shaft arranged transverse to the engine shaft, speed-reducing gearing for the motor at the other side of the engine shaft connected with the armature shaft of the motor, a gear on the engine shaft, and a pinion positioned intermediate of the motor and gearing meshing with the gear on the engine shaft and connected with the gearing for effecting an en- 125

ions 20 and 21 which mesh with such a larger engine-starting pinion being correspondingly reduced, the several sets of teeth, however, still being so spaced as to secure the hereinbefore described stepping forward wedging or cam action, and also in this case additionally securing a further reduction due to the usual lever action of the interengaging pinions of different diameters. However, for simplicity of construction, I prefer to employ abutment and reducing pinions or gears, such as 11 and 12, of equal diameters but with a slightly different number of teeth, and uniformly diametered planetary pinions, such as 20 and 21, of any suitable diameter and number of teeth.

The engine-starting sleeve 17 is shown as disposed in a plane at right angles to the engine shaft 1 and is permanently rotatively connected to the engine shaft 1 through spiral reducing gearing which, in the engine starter illustrated in the drawings, gives a further reduction of one to three, making a total speed reduction from the armature shaft 7 to the engine shaft 1 of one to forty-two. The spiral gearing includes a spiral-toothed gear 22, constituting an engine-connected member, fixed on the engine shaft 1, which in the construction shown also constitutes a starter shaft, and a combined spiral-toothed pinion and clutch member 23 splined on the engine-starting sleeve 17 to rotate therewith but left free to be shifted longitudinally. The spiral teeth of the gear 22 and of the pinion 23 are disposed at a suitable angle to permit either the gear or the pinion to be the driver, the angle of the teeth, as shown in the drawings, being forty-five degrees, but other suitable angles could be used, for example, the spiral teeth on the pinion could be at thirty-five degrees to a plane of rotation and those on the gear at fifty-five degrees.

The end of the spiral-toothed pinion 23 adjacent the gearing carrier 8 has formed thereon a clutch member 23^a, shown as having inclined clutch teeth projecting toward the gearing carrier. The adjacent part of the gearing carrier 8 has thereon a clutch member 8^a provided with clutch teeth inclined correspondingly to those of the clutch member 23^a and adapted to coöperate therewith. The inclination or direction of twist of the teeth of the spiral-toothed pinion 23 and the spiral-toothed gear 22 is such that the end thrust developed thereby will hold the clutch member 23^a out of engagement with the clutch member 8^a when the spiral-toothed pinion 23 is driven by its sleeve 17 in the engine-starting operation, the direction of the engine-starting torque being indicated by the arrows 24 in Figs. 2 and 5. The spiral-toothed pinion 23 has a sleeve portion extending back to the journal box 16 adjacent to the dynamo-motor 6 where it is pro-

vided with ball bearings, including a supporting bearing and a thrust bearing.

When the engine is started, its speed under self-actuation is immediately accelerated so that there is a reversal of torque and rotation at an increased rate is transmitted from the engine connected spiral-toothed gear 22 to the spiral-toothed pinion 23 in the same direction in which it has been moving in effecting the starting of the engine. The immediate or first result is that the side thrust of the spiral-toothed gear 22, in the direction indicated by the arrows 25 in Figs. 2, 5 and 7, transmits end thrust to the spiral-toothed pinion 23 in the direction to shift the spiral-toothed pinion along the outer sleeve 17 and to bring about the engagement of the clutch member 23^a, carried by the spiral-toothed pinion 23, with the clutch member 8^a, carried by the adjacent gearing carrier part 8, the perpendicular faces of the coöperating clutch teeth engaging and rotatively locking the gearing carrier 8 to the spiral-toothed pinion 23 to rotate therewith and to be driven thereby.

When the spiral-toothed pinion 23 is rotatively locked to the gearing carrier 8, the dynamo-motor 6 will be actuated as a dynamo directly through the gearing carrier 8 from the spiral-toothed pinion 23 through the interengaged clutch members 23^a and 8^a without relative movement of the parts of the gearing, the planetary pinions 20 and 21, the engine-starting pinion 12 and the abutment pinion 11 all moving idly together with the gearing carrier 8, the undirectional clutch or ratchet device 14-15 permitting such rotation of the abutment pinion 11 and its anchor sleeve 13, the armature shaft 7, inner sleeve 13 and outer sleeve 17 now all rotating together, the inner and outer sleeves 13 and 17 now merely rotating idly, the power of the engine being transmitted through the gear 22, pinion 23, gearing carrier 8 and clutch 9 to the armature shaft 7. The dynamo-motor will now be actuated as a dynamo at a higher ratio of speed transmitted from the engine shaft 1 than the ratio of speed which as a motor it transmitted to such engine shaft, and such ratio will, in the construction illustrated, be at the multiplied rate of three to one, brought about by the spiral gearing 22-23. The entire arrangement is such as to permit the use of a small and compact high-speed dynamo-motor. When the dynamo-motor is actuated as a dynamo, it is employed to effect the storage of electrical energy which may be utilized in the engine-starting operation. Also, of course, such stored electrical energy may be otherwise utilized, such as for providing lighting and ignition current, et cetera. Also, of course, for other than engine-starting purposes, current may be taken directly from the dynamo-motor,

17. An engine starter comprising, in combination, an engine-connected member, a dynamo-motor at one side of the engine-connected member, speed-reducing gearing at the other side of the engine-connected member connected with the engine-connected member and with the dynamo-motor to effect an engine-starting operation through the gearing from the dynamo-motor operated as a motor, and power-transmitting connections connecting the speed-reducing gearing and the engine-connected member including automatically acting clutching means for connecting the engine-connected member with the dynamo-motor and discontinuing the operation of the speed-reducing gearing to operate the dynamo-motor as a dynamo without the operation of the speed-reducing gearing.

18. An engine starter comprising, in combination, an engine-connected gear, an engine-starting electric motor at one side of such gear having an armature shaft arranged transverse to the axis of such gear, speed-reducing gearing for the motor at the other side of the engine-connected gear connected with the armature shaft of the motor, and a pinion meshing with the engine-connected gear and connected with the speed-reducing gearing to effect an engine-starting operation from the motor through the speed-reducing gearing.

In testimony whereof I have affixed my signature in presence of two witnesses.

HENRY GIBSON O'NEILL.

Witnesses:

HENRY D. WILLIAMS,
WILLIAM ASHLEY KELLY.
